SHEET TRANSFER MECHANISM

Charles F. Root, Cleveland, Ohio, assignor to The Chandler & Price Company, Cleveland, Ohio, a corporation of Ohio

Application November 26, 1941, Serial No. 420,546

18 Claims. (Cl. 101—287)

This invention relates as indicated to sheet transfer mechanism and more particularly to sheet delivery means for use in conjunction with platen presses of the well-known Gordon type.

The sheet delivery mechanism of this invention constitutes an improvement over the device disclosed in my issued Patent No. 1,884,258 and is particularly advantageously employed in conjunction with a sheet feeding mechanism of the type disclosed in my Patent No. 2,260,684. In platen printing presses, when both the feed and delivery tables are mounted at the front of the press (i. e., adjacent the upper edge of the platen), difficulty is encountered in arranging such tables so that any considerable quantity of sheets can be printed without replenishment of the feed stack or removal of accumulated sheets from the delivery table. With the feed table below the delivery table trouble arises, since as the feed table progressively rises and the delivery table progressively descends, the two would soon interfere with each other. When employing feed and delivery tables at the front of the press, the feed table being above the delivery table, it has been necessary for the feeding mechanism to carry the sheet being fed in a path of movement above that of the sheet being delivered by the sheet delivery mechanism. This has involved a somewhat complex operating structure and a nice adjustment of parts to prevent interference between the feeding and delivery mechanism. Also, the tops of the stacks will be at inconvenient levels for operation of the sheet transfer means. Or, instead of vertically movable tables, elaborate conveyor means may be provided. On the other hand, it has been found very desirable to employ sheet feeding mechanism of the type disclosed in my Patent No. 2,260,684 since the same is relatively simple in its movements and yet capable of delicate and precise adjustment.

It is therefore a primary object of my invention to provide sheet delivery mechanism whereby a sheet may be removed or delivered from the platen in a path of movement above the path of movement of a sheet in course of being simultaneously fed to the platen from a stack located adjacent the forward or upper edge of the platen.

Another object of my invention is to provide a novel sheet picker assembly incorporating adjusting means which also acts as a safety device to prevent improper mounting of the sheet picker means.

Another object of my invention is to provide means for synchronizing the rise of a feed table located at the front of the press with the descent of a delivery table located laterally of the press.

Other objects of my invention will appear as the description proceeds.

To the accomplishment of the foregoing and related ends, said invention, then, consists of

the means hereinafter fully described and particularly pointed out in the claims.

The annexed drawings and the following description set forth in detail certain mechanism embodying the invention, such disclosed means constituting, however, but one of various mechanism forms in which the principle of the invention may be used.

In said annexed drawings:

10 Fig. 1 is a side elevational view of a platen printing press showing my new sheet delivery mechanism mounted laterally thereof;

15 Fig. 2 is a front elevational view of the press showing my new delivery mechanism and a portion of the sheet feeding mechanism;

Fig. 3 is a fragmentary top plan view of the press showing the action of my sheet delivery and sheet feeding means;

20 Fig. 4 is a fragmentary top sectional view of the mechanism for elevating the feed table and lowering the delivery table in synchronism;

Fig. 5 is a side elevational view of the feed table elevating mechanism taken along the line 5—5 on Fig. 4;

25 Fig. 6 is a top sectional view taken along the line 6—6 on Fig. 1 of the means for operating the sheet delivery mechanism;

Fig. 7 is a fragmentary elevational view of a portion of the sheet picker assembly showing adjusting means therefor;

30 Fig. 8 is an elevational view of such assembly taken along the line 8—8 on Fig. 7; and

Fig. 9 is a top view of the portion of such assembly illustrated in Fig. 7.

Now referring more specifically to the drawings, mounted across the front of frame 1 of the press is a cam shaft 2 adapted to be driven through gear 3. Also mounted at the front of the press is a feed table 3 adapted to carry a stack of sheets 5 which are fed to the platen 6 of the press by sheet feeder bar 7, such feeder bar being carried by a feeder bar carrier 8 which is pivotally mounted on the press at its lower end 9 and adapted to be actuated in the manner

40 explained in my aforesaid patent. Mounted laterally of the press is a delivery table 10 adapted to receive sheets 11 deposited thereon by sheet delivery bar 12 in the manner to be described below.

50 Bracket frame member 13, mounted laterally of the press, has the end of cam shaft 2 journaled therein and also serves as the support upon which the delivery table mechanism is mounted. Also mounted on the side of the press

55 is a cylinder 14 having a vacuum line 15 communicating with the lower end thereof, and an upright tubular member 16 fitting in its upper end for reciprocation therein. A bracket 17, likewise attached to the frame of the press, additionally supports member 16 while permitting vertical reciprocation of the latter. Freely piv-

totally mounted about the lower portion of member 16 is a member 18 spaced from cylinder 14 by a washer 19 and bearing rocker arms 20 and 21. Arm 20 is connected by means of a ball and socket joint with link 22 (see Figs. 1 and 6) which is in turn connected at its other end by ball and socket means with the upper end of lever 23 pivotally mounted on the frame of the press. A cam roller 24 carried by such lever is held in engagement with cam 25 keyed to cam shaft 2 by means of a tension spring 26. It will thus be seen that as cam 25 rotates, link 22 will be reciprocated to oscillate rocker arm 20 and consequently also arm 21.

Fixedly clamped to member 16 is a member 27 carrying a depending slide or finger 28 adapted to engage the slotted end of arm 21 wherein vertical reciprocation is facilitated by roller 29. A horizontal cam track is also provided between flanges 30 and 31 wherein roller 32, mounted on the end of lever 33, is adapted to move. Lever 33 is pivotally mounted on bracket 13 and carries at its other end a cam roller 34 held in engagement with cam 35 by means of tension spring 36. Thus as cam 35 revolves, lever 33 will be rocked to cause vertical reciprocation of member 16, finger 28 sliding in the end of arm 21. Moreover, since, as above indicated, member 27 is fixedly positioned on member 16, as arm 21 is oscillated by action of cam 25, as above described, member 16 will be caused to pivot about its vertical axis. Since arm 37, which supports the delivery picker bar 12, is carried by the upper end of member 16, such arm and picker bar will be oscillated from a position 38 (see Fig. 3) over the platen to the position shown in solid line in Figs. 1 to 3 inclusive. Cam 35 is shaped so that the delivery picker means will be rather abruptly elevated as it quits the platen and maintain such elevation as it swings to the delivery table laterally of the press. In this fashion it is enabled to avoid interference with feeder bar 7 which is simultaneously in process of moving from feed table 4 to position 39 on the platen.

The vertical member or support 16 which thus serves as the delivery picker bar carrier has a laterally offset upper end portion 40 terminating in an upwardly directed portion on which a tubular picker bar supporting bracket 41 is sleeved for pivotal movement relative thereto. As shown in Fig. 7 (and also in dotted outline in Figs. 1 and 2), such laterally offset portion 40 is inclined to the axis of support 16, i. e., to the vertical, at a slightly obtuse angle. This angle corresponds with the angle of inclination of the platen 6 when in open position, as shown in dotted outline in Fig. 1. In other words, the picker bar is mounted on such end portion 40 of support 16 about an axis inclined to the axis of said support substantially the same as the angle of inclination of such platen when in open position. It follows that angular adjustment of arm 37 about portion 40 (such adjustment being accomplished by means now to be described) will serve to swing the picker bar 12 in a plane parallel to that of the platen.

Tubular arm 37, carried by such bracket member, is telescopically extensible in the usual manner as is the picker bar 12 and all such tubular members communicate one with another so that when suction is applied through line 15 such suction will enable sucker tips 42 to seize the sheet to be delivered. The picker bar 12 is furthermore secured to the end of arm 37 in the usual manner so as to be angularly adjustable about

an axis parallel to that about which the arm is adjustable on support 16. For the latter purpose, clamping means 43 is provided for locking bracket 41 in the desired pivotal position and additional adjusting and safety means is provided to facilitate proper locating of the delivery picker bar and to prevent damage should the operator inadvertently neglect to tighten clamp 43. Such adjusting and safety means comprises a screw 44 mounted in threaded bracket 45 on offset portion 40 of vertical member 16. A knurled lock nut 46 is provided to lock the screw in desired position. A depending finger 47 is carried by arm 48 extending from bracket member 41 and such finger is received between spaced discs 49 and 50 carried by such screw. It will therefore be clear that as screw 44 is turned, arm 37 will be correspondingly swung and the position of picker bar 12 may be delicately adjusted relative to the position of the sheet to be picked from the platen. Furthermore, once bracket member 41 has been sleeved in place with finger 47 between the two discs, it is obvious that arm 37 cannot swing freely when the press is started in operation even when the operator has momentarily forgotten to tighten clamp 43. A not uncommon source of damage to the mechanism is thereby precluded.

The feed table 4 at the front of the press is carried by a column 51 slidably mounted in bracket 52 and adapted to be elevated by pinion 53 engaging rack teeth 54 on such column. Such pinion in turn is mounted on a shaft 55 adapted to be driven through pawl and ratchet means responsive to the action of a feeler finger on the top 35 of the stack of sheets 5 carried by table 4. A cam 56 operative to rock arm 57 and thereby reciprocate link 58 supplies the power to such pawl and ratchet means for elevating the table. The pawl and ratchet means is of conventional type well known in such devices and is therefore not shown in detail. Clutch means 59 operated by lever 60 is provided to disengage the driving means when it is desired to manually adjust the position of the table by rotation of hand wheel 61.

Delivery table 10 is carried on a column 51' slidably in upper bracket 52' supported by bracket 13. Such delivery table is of course positioned laterally of the press and therefore at right angles to feed table 4. Furthermore, as shown in Fig. 2, said delivery table is tilted toward the adjacent side of the press so that the successive sheets as dropped thereon by picker bar 12 will be correspondingly inclined. As a matter of fact, the sheets will be laid on the table in a plane approximately parallel to the plane of the latter due to the angular disposition of laterally offset portion 40 of support 16. Like parts in the delivery table operating mechanism will be designated by the same numbers employed in identifying the parts of the feed table mechanism, such numbers being primed. No pawl and ratchet mechanism is provided to lower the delivery table as sheets are stacked thereon, but a gear 62 is provided on shaft 55 and engaging a worm 63 on shaft 63 which carries a sprocket 64 adjacent one end. Rotation of gear 62 is operative to rotate shaft 55 and pinion 53 through the intermediary of clutch 59. It is the rotation of such shaft 63 by the aforesaid pawl and ratchet means which is therefore operative to elevate the feed table. A similar gear 62' is mounted on shaft 55' and operative to rotate such shaft through clutch 59'. Gear 62' is adapted to be driven by a worm 65 on shaft 63', a sprocket 64' being keyed to the other end of such shaft. A chain 66

connects sprockets 64 and 64' so that as the feed table is elevated by rotation of shaft 63, shaft 63' will likewise be rotated to lower the delivery table in synchronism therewith. It is obvious that since pinions 53 and 53' are on opposite sides of their respective columns 51 and 51', column 51' will be lowered as column 51 is elevated.

Back member 67 operative to position stack 11 on delivery table 10 is carried by a bracket 68 adjustable back and forth by rotation of handle 69 operative to rotate a pinion engaging rack 70.

The operation of the mechanism of this invention is believed to be obvious from the foregoing description and it will be seen that a sheet delivery mechanism has been provided which is operative to deliver a sheet from the platen to a delivery table laterally of the press, the path of movement of such delivery mechanism being above the path of movement of the sheet in course of being simultaneously fed to the platen from the stack located at the front of the press. It will furthermore be seen that such mechanism is capable of quick adjustment to accommodate various sizes of sheets and when once properly adjusted is entirely automatic in action.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In platen presses and the like, sheet delivery means operative to deliver a sheet laterally of the press, said sheet delivery means comprising sheet picker means, picker carrier means, means for reciprocating said picker carrier means substantially vertically, and means for pivotally moving said picker carrier means to swing said sheet picker means from a position above the platen of such press to a position laterally of such press in such timed relation to such reciprocation that said sheet picker means are first substantially elevated from a position where direct engagement is had with a sheet upon such platen prior to said means being swung laterally.

2. In platen presses and the like, sheet delivery means operative to deliver a printed sheet laterally of the press, said sheet delivery means comprising sheet picker means, picker carrier means, cam means operative to reciprocate said picker carrier means substantially vertically, and other cam means operative to rotate said picker carrier means about a substantially vertical axis to swing said sheet picker means from a position immediately above the platen of such press to a position laterally of such press in such timed relation to such reciprocation that said sheet picker means are immediately elevated from a position where direct engagement is had with a sheet upon such platen prior to said means being swung laterally.

3. In platen printing presses and the like, sheet feeding means operative to feed a sheet to the platen of such press, sheet delivery means operative to deliver a printed sheet laterally of the press in timed relation with the action of sheet feeding mechanism operative to feed a sheet to the platen of such press from a stack located adjacent the upper edge of such platen, said delivery means comprising an arm pivotally mounted adjacent the side of such press, sheet picker means carried by said arm, means for swinging said arm to move said picker means from a posi-

tion immediately above such platen to a position laterally of such press, and means operative to raise said arm to elevate said picker means from a position where direct engagement is had with a sheet upon such platen sufficiently to pass above such sheet feeding means in process of feeding a sheet to such platen prior to said means being swung laterally.

4. In platen printing presses and the like, sheet feeding means operative to feed a sheet to the platen of such press from a stack located adjacent the upper edge of such platen and sheet delivery means operative to deliver a sheet from such platen to a position laterally of such press, said sheet delivery means comprising an upright member, an arm mounted on the upper end of said member, sheet picker means carried by said arm, means for swinging said arm to move said sheet picker means from a position immediately above such platen to a position laterally of such press, and cam means for reciprocating said member to elevate said sheet picker means sufficiently from a position where direct engagement is had with a sheet upon such platen to pass above said sheet feeding means in process of feeding a sheet to such platen prior to said means being swung laterally.

5. In platen printing presses and the like, sheet transfer means comprising a vertically reciprocable member mounted laterally of such press for pivotal movement about its vertical axis, a lever pivotally mounted on the frame of said press intermediate of its ends, a cam engaging one end of said lever and operative to rock the same, the other end of said lever engaging said member whereby said member may be vertically reciprocated, an arm attached to said member for rotation therewith, another lever mounted on such frame, link means connecting said last named lever and arm, cam means operative to rock said last-named lever to rotate said member, and sheet picker means carried by the upper end of said member and adapted to swing from a position immediately above the platen of such press to a position laterally of such press as said member rotates, said cams being disposed to cause substantially vertically upward movement of said member from a position where direct engagement is had with a sheet upon such platen before said picker means begins its swinging movement away from such platen.

6. In platen printing presses and the like, sheet delivery means comprising a vertically reciprocable member mounted laterally of such press for pivotal movement about its vertical axis, a lever pivotally mounted on the frame of said press intermediate of its ends, a cam engaging one end of said lever and operative to rock the same, a cam roller on the other end of said lever, a cam way on said member engaging said cam roller whereby said member may be vertically reciprocated, an arm pivotally mounted on said member, vertically disposed slide means connecting said arm and member whereby said arm and member will be caused to rotate together but said member may be reciprocated without causing vertical movement of said arm, another lever mounted on such frame, link means connecting said last named lever and arm, cam means operative to rock said last-named lever to rotate said member, and sheet picker means carried by the upper end of said member and adapted to swing from a position immediately above the platen of such press to a position laterally of such press as said member rotates, said cams being disposed to

cause substantially vertically upward movement of said member from a position where direct engagement is had with a sheet upon such platen before said picker means begins its swinging movement away from such platen.

7. In platen printing presses and the like, sheet picker means comprising a picker bar carrier having a laterally offset upper end portion, a picker bar supporting bracket mounted on said offset portion for pivotal movement about a substantially vertical axis, and means associated with said picker bar carrier for adjustably setting the pivotal location of said bracket relative to said picker bar carrier.

8. In platen printing presses and the like, sheet picker means comprising a substantially vertical tubular member having a laterally offset upper end portion terminating in an upwardly directed portion, a tubular picker bar supporting bracket sleeved on said upwardly directed terminal portion for pivotal movement relative thereto, clamping means for locking said bracket in desired pivotal position, a depending finger carried by said bracket, a screw mounted on said offset portion of said vertical tubular member, and a pair of spaced disks carried by said screw adapted to receive the end of said finger therebetween, said bracket being adjustably positioned by rotation of said screw and held in desired pivotal position thereby even when said clamping means has not been properly tightened.

9. In platen printing presses and the like, sheet picker means comprising a substantially vertical member, a laterally extending picker bar supporting arm mounted on said vertical member for pivotal movement about a substantially vertical axis, a depending finger carried by said laterally extending arm, a screw mounted on said vertical member, and a pair of spaced disks carried by said screw and adapted to receive said finger therebetween.

10. In platen printing presses and the like, sheet picker means comprising a substantially vertical tubular member, a laterally extending tubular picker bar supporting arm sleeved on the upper end of said vertical member for pivotal movement relative thereto, a depending finger carried by said laterally extending arm, a screw mounted on said vertical member, a pair of spaced disks carried by said screw and adapted to receive said finger therebetween, and a tubular sheet picker bar carried by said tubular arm and communicating therewith.

11. In platen presses and the like, a sheet transferring device including a vertical support both reciprocable longitudinally of and oscillatory about its axis, said support having a laterally offset upper end portion inclined to the axis of said support at an angle substantially the same as that of the platen when in open position and terminating in a rectangularly related, upwardly directed portion, and a picker bar carried by said last-named portion disposed in one oscillatory position of said support to extend over such platen.

12. In platen presses and the like, a sheet transferring device including a vertical support both reciprocable longitudinally of and oscillatory about its axis, said support having a laterally offset upper end portion inclined to the axis of said support at an angle substantially the same as that of the platen when in open position and terminating in a rectangularly related, upwardly directed portion, and a picker bar carried by said last-named portion disposed in one oscillatory

position of said support to extend over such platen, said picker bar being angularly adjustable about the axis of said last-named portion.

13. In platen presses and the like, a sheet transferring device including a vertical support both reciprocable longitudinally of and oscillatory about its axis, said support having a laterally offset upper end portion inclined to the axis of said support at an angle substantially the same as that of the platen when in open position and terminating in a rectangularly related, upwardly directed portion, and a picker bar carried by said last-named portion disposed in one oscillatory position of said support to extend over such platen, said picker bar being angularly adjustable about the axis of said last-named portion and about a parallel axis spaced from such first-named axis.

14. In platen presses and the like, a sheet transferring device including a vertical support both reciprocable longitudinally of and oscillatory about its axis, said support having a laterally offset upper end portion inclined to the axis of said support at an angle substantially the same as that of the platen when in open position and terminating in a rectangularly related, upwardly directed portion, a bracket mounted on such upwardly directed portion for pivotal movement about the axis thereof, a picker bar carried by said bracket, and means for adjustably setting the pivotal location of said bracket relatively to such laterally offset upper end portion.

15. In platen presses and the like, a sheet transferring device including a vertically extending support both reciprocable longitudinally of and oscillatory about its axis, said support having a laterally offset upper end portion, and a picker bar adjustably mounted on said portion about an axis inclined to the axis of said support.

16. In platen presses and the like, a sheet transferring device including a vertically extending support both reciprocable longitudinally of and oscillatory about its axis, said support having a laterally offset upper end portion, an arm adjustably mounted on said portion about an axis inclined to the axis of said support, and a picker bar adjustably mounted in turn on said arm about an axis parallel with the axis of the latter.

17. In platen presses and the like, wherein the platen is inclined to the vertical when in open position, a sheet transferring device including a vertically extending support both reciprocable longitudinally of and oscillatory about its axis, said support having a laterally offset upper end portion, and a picker bar adjustably mounted on said portion about an axis inclined to the axis of said support substantially the same as the angle of inclination of such platen when in open position.

18. In platen presses and the like, wherein the platen is inclined to the vertical when in open position, a sheet transferring device including a vertically extending support both reciprocable longitudinally of and oscillatory about its axis, said support having a laterally offset upper end portion, an arm adjustably mounted on said portion about an axis inclined to the axis of said support substantially the same as the angle of inclination of such platen when in open position, and a picker bar adjustably mounted on said portion about an axis parallel with the axis of said arm.
